UNITED STATES PATENT OFFICE.

ANTHONY B. HUENINGHAKE AND JOHN THOMAS KENNEDY, OF CINCINNATI, OHIO.

DEODORIZER.

1,186,988.

Specification of Letters Patent. Patented June 13, 1916.

Application filed June 24, 1915. Serial No. 36,140.

To all whom it may concern:

Be it known that we, ANTHONY B. HUENINGHAKE and JOHN T. KENNEDY, both citizens of the United States, and both residents of the city of Cincinnati, in the county of Hamilton and State of Ohio, have invented certain new and useful Improvements in Deodorizers, of which the following is a specification.

10 The object of our invention is to provide a highly efficient deodorizer, which will be cheap of manufacture, and simple in construction.

One of the salient features of our invention is to form an outside jacket or casing whose entire surface is filled with small perforations or slots so that the disinfectant fluid or deodorizer is rendered capable of being emitted in all directions so that a large 20 area is covered by its sanitary influences.

Another salient feature consists in providing an inner tube or can spaced from the outer perforated jacket and provided at its periphery with a felt, cloth wick, or other 25 material suitable for allowing the disinfectant fluid to permeate it by capillary attraction.

The other features of the invention and its advantages will readily become apparent 30 from the following specification.

Figure 1, is a perspective view of our invention partly broken away on one side to illustrate its construction, Fig. 2, is a perspective view of the inner can or tube partly broken away on one side to illustrate construction, and Fig. 3, is a central longitudinal section of the invention.

The outer jacket 1 is preferably cylindrical in shape and has a bottom 2 and a top 3, the bottom is put in place by a seam and the lid 3 is removable. In order to hold the lid in place a pin 4 is rigidly connected to the jacket 1 and a spring 5 connected at point 6 to the said jacket 1, its loose end 7 passing through a hole in the casing, the lid 3 provided with perforations 8 into which the pin 4 and end 7 of spring 5 enter to hold said lid in place. If it is desired to remove said lid 3 the end 7 of spring 5 is pushed in and the lid can be removed. The jacket 1 and its bottom 2 and top 3, except around its rim 9 are all perforated and this may be perforated if desired. Another fastening device may be used for holding the lid on the jacket. This jacket and its top and bot-

tom may be made of any size, from any material and of any contour. The inner can or tube 10 is less in diameter than the jacket 1 so that a space 12 is left between it and said jacket. At its lower end this can 10 is provided with a screw cap connection 13 through the medium of which it is filled, and at its lower extremity the can 10 is also provided with a circular trough or spaced cap 14, a space 15 being left by this formation.

Around the periphery of the can 10 we place a wick or like covering 16, which may be of any size, weight or contour desired and extend partly or entirely over the can 10, as will be found desirable.

On the outer surface of the spaced cap or trough 14 we place legs or supports 17 to hold the can 10 off of the bottom 2 of the jacket 1. These legs may however be dispensed with and the can 10 supported in the jacket 1 in any desirable manner found expedient.

A small hole or perforation 18 is placed near the bottom of the can 10 through which the fluid, liquid or contents of the can pass out and permeate the wick 16. This wick 16 may be removably or detachably connected to the can 10, in the present instance being removably attached so that it can be slid off.

The device is portable and can be placed at any point or position where needed. In the present instance we provide arms as 20 by which is can be attached to the wood-work or frame.

In order to place the device in operation, the screw cap connection 13 on can 10 is opened by unscrewing the cap thereof and the deodorizing or disinfecting fluid poured into the said can 10 and when sufficiently filled the can is screwed home. The lid 3 having been removed from the jacket 1, the can 10 is placed into the jacket, the feet 17 resting on bottom 2; the liquid will seep or drain out through the hole 18 and permeate the wick 16 and by capillary attraction rise and soak the whole wick, until it is thoroughly filled with the fluid used for deodorizing or disinfecting. When the wick becomes too dry and is not sufficiently soaked to act as a good germicide or disinfectant, the can 10 may be refilled. The trough 14 catches all refuse or leakage or sediment and keeps the device clean at its lower end.

We may use any kind of deodorizer, disinfectant or the like and place the deodorizer at any point where its use is needed.

By reason of the jacket being wholly perforated and jacket and inner can spaced all possible disinfecting and deodorizing qualities emanating from the liquid used will thoroughly permeate the atmosphere in all directions at the point where the device is used, not only on account of this peculiar construction but inasmuch as the air, wind or draft or the like can circulate through the jacket and space between it and the inner can.

15 While we have described one specific form and construction of our device, it will readily be apparent that the same is capable of considerable modification, and we wish to be understood as claiming that such modifications will not deviate from the principle and spirit of our invention, and still fall within the scope of our invention.

What we claim as new and our invention and desire to secure by Letters Patent is:

25 1. In a deodorizer of the class described, a perforated jacket, a can within said jacket and spaced apart therefrom, said can holding the deodorizing element, means for opening and closing said can, an absorbing material around said can, and a vent hole in the side of the can for allowing the deodorizing element to directly reach the absorbing material, the perforated jacket having a perforated top and bottom.

30 2. In a deodorizer of the class described,

Copies of this patent may be obtained for five cents each, by addressing the "Commissioner of Patents, Washington, D. C."

a perforated jacket, a can for holding the liquid within the same and spaced apart therefrom, said can provided with a trough attached thereto at the bottom, an absorbing wick around said can, a vent in the can to allow the liquid to directly reach the absorbing wick.

3. In a deodorizer of the class described, a perforated jacket, a liquid holding can within the same and spaced apart therefrom, means for opening and closing said can, a trough at the bottom of said can and legs on the trough for supporting the can in the jacket, a wick around said can, and a hole in the can near the bottom thereof for allowing the liquid in the can to directly saturate the wick.

4. In a deodorizer of the class described, a jacket perforated throughout its entire extent and a perforated top and bottom therefor, a can for holding the liquid, a trough connected to said can at the bottom and having legs for supporting the can in the jacket, said can spaced apart from said jacket, the can at its bottom having a screw cap which extends into a space between the bottom of the can and the bottom of the jacket, a wick surrounding said can, a hole in said can near its bottom for allowing the liquid to directly reach the wick.

ANTHONY B. HUENINGHAKE.
JOHN THOMAS KENNEDY.
